(57) **CLAIM**

The ornamental design for the glass smoking pipe, as shown and described.

DESCRIPTION

FIG. 1 is a Front, left-side, upper perspective view of a first embodiment of the glass smoking pipe.

FIG. 2 is a Back, left-side, upper perspective view of a first embodiment of the glass smoking pipe.

FIG. 3 is a Left side view of a first embodiment of the glass smoking pipe.

FIG. 4 is a Right side view of a first embodiment of the glass smoking pipe.

FIG. 5 is a Front view of a first embodiment of the glass smoking pipe.

FIG. 6 is a Back view of a first embodiment of the glass smoking pipe.

FIG. 7 is a Top view of a first embodiment of the glass smoking pipe.

FIG. 8 is a Bottom view of a first embodiment of the glass smoking pipe.

FIG. 9 is a Front, left-side upper perspective view of a second embodiment of the glass smoking pipe.

FIG. 10 is a Back, left-side, upper perspective view of a second embodiment of the glass smoking pipe.

FIG. 11 is a Left side view of a second embodiment of the glass smoking pipe.

FIG. 12 is a Right side view of a second embodiment of the glass smoking pipe.

FIG. 13 is a Front view of a second embodiment of the glass smoking pipe.

FIG. 14 is a Back view of a second embodiment of the glass smoking pipe.

FIG. 15 is a Top view of a second embodiment of the glass smoking pipe.

FIG. 16 is a Bottom view of a second embodiment of the glass smoking pipe.

FIG. 17 is a Front, left-side, upper perspective view of a third embodiment of the glass smoking pipe.

FIG. 18 is a Back, left-side, upper perspective view of a third embodiment of the glass smoking pipe.

(Continued)

FIG. 19 is a Left side view of a third embodiment of the glass smoking pipe.
FIG. 20 is a Right side view of a third embodiment of the glass smoking pipe.
FIG. 21 is a Front view of a third embodiment of the glass smoking pipe.
FIG. 22 is a Back view of a third embodiment of the glass smoking pipe.
FIG. 23 is a Top view of a third embodiment of the glass smoking pipe.
FIG. 24 is a Bottom view of a third embodiment of the glass smoking pipe.
FIG. 25 is a Front, left-side, upper perspective view of a fourth embodiment of the glass smoking pipe.
FIG. 26 is a Back, left-side, upper perspective view of a fourth embodiment of the glass smoking pipe.
FIG. 27 is Left side view of a fourth embodiment of the glass smoking pipe.
FIG. 28 is a Right side view of a fourth embodiment of the glass smoking pipe.
FIG. 29 is a Front view of a fourth embodiment of the glass smoking pipe.
FIG. 30 is a Back view of a fourth embodiment of the glass smoking pipe.
FIG. 31 is a Top view of a fourth embodiment of the glass smoking pipe; and,
FIG. 32 is a Bottom view of a fourth embodiment of the glass smoking pipe.
